(57) **CLAIM**

The ornamental design for an encapsulated RFID chip, as shown and described.

DESCRIPTION

FIG. 1 is an isometric view of a first variant of an encapsulated RFID chip in accordance with the design.

FIG. 2 is an elevation view of the encapsulated RFID chip in FIG. 1.

FIG. 3 is an isometric view of a second variant of an encapsulated RFID chip in accordance with the design.

FIG. 4 is an elevation view of the encapsulated RFID chip in FIG. 3.

FIG. 5 is an isometric view of a third variant of an encapsulated RFID chip in accordance with the design.

FIG. 6 is an elevation view of the encapsulated RFID chip in FIG. 5.

FIG. 7 is a top plan view of an encapsulated RFID chip as in any of FIGS. 3 through 6.

FIG. 8 is a bottom plan view of an encapsulated RFID chip as in any of FIGS. 3 through 6.

FIG. 9 is a top plan view of an encapsulated RFID chip as in FIGS. 1 and 2; and,

FIG. 10 is a bottom plan view of an encapsulated RFID chip as in FIGS. 1 and 2.
